mann & Co., West New York, N. J., a corpora-
tion of New Jersey

Application May 11, 1949, Serial No. 92,534

9 Claims. (Cl. 66—149)

1

This invention relates to mechanism for drawing off the fabric incident to its formation in textile machines. More particularly, it is concerned with fabric take-up means useful in connection with straight stocking knitting machines of the "cotton" type wherein the flat stocking blanks are drawn from the knitting needles and wrapped upon take-up rolls or reels.

Due to the changing width of flat stocking blanks produced in such machines, it is essential, if tearing, stretching or deformation of the fabric is to be avoided, to compensatively vary the tension induced by the take-up rolls as the blanks are being knitted. Mechanisms heretofore devised for this purpose either entailed the exercise of judgment on the part of skilled operators to make adjustments at different times during the knitting of the stocking blanks, or were very complicated and not wholly reliable in their operation.

Our invention is directed toward overcoming the foregoing drawbacks, this desideratum being realized in practice, as hereinafter more fully disclosed, through provision of a simple and relatively inexpensive mechanism comprising a slip clutch for driving the draw-off roll, means automatically operative to change torsional influence of the clutch upon the roll at predetermined times and so vary the tension upon the fabric as desired or required, a second normally inactive slip clutch having the tendency to reversely rotate the roll to partially counteract the torsional influence of the first clutch to correspondingly relieve the tension on the fabric during the welt closing and fashioning phases of the knitting cycle, and supplemental means automatically operative to control the functioning of said second slip clutch.

Other objects and attendant advantages will appear from the following detailed description of the attached drawings, wherein:

Fig. 1 is a skeletonized view in transverse section, of a flat fashioned stocking knitting machine with incorporated fabric take-up mechanism conveniently embodying our invention.

Fig. 2 is a fragmentary view showing the take-up roll and the associated slip clutches in longitudinal section, and diagrammatically, the means by which the operation of said clutches is automatically controlled.

Fig. 3 is a fragmentary detail view in top plan looking as indicated by the angled arrows III—III in Fig. 2.

Fig. 4 is a fragmentary view partly in elevation and partly in axial section taken as indicated by the angled arrows IV—IV in Fig. 2; and

2

Fig. 5 is a wiring diagram showing the connections between various electrical instrumentalities employed in the mechanism.

With more detailed reference first more specifically to Figs. 1 and 2 of these illustrations, the numeral 10 designates the take-up roll of the knitting machine by which the stocking blank S is drawn horizontally away from the needles 11 as it is being knitted in a well known way. The roll 10 is provided with pull straps, such as the one indicated at 12 in Fig. 2, for releasable connection to the ends of a rod 13 inserted into the fold of the welt W of the stocking blank after said welt has been closed, for example, by automatic mechanism (not shown), likewise in a well known way. Adjacent one end, the shaft 15 of the take-up roll 10 is rotatively supported in a bearing 16 on one of the transverse frames 17 of the knitting machine, and it is to be understood that it is similarly supported at the opposite end.

For the purpose of imparting controlled yielding rotary motion to the take-up roll 10 in accordance with our invention, we have mounted on the outward end of its shaft beyond the bearing 16, two slip clutches 18 and 19 of the electromagnetic fluid type which are provided with sheaves 20 and 21 respectively. Through belts 22 and 23, rotary motion is imparted to the clutches 18 and 19 by two smaller sheaves 25 and 26 on a counter shaft 27 which is journaled in a bearing bracket 17a extending laterally from the frame 17. Affixed to the counter shaft 27 with the sheaves 25 and 26, is a larger sheave 28 which is in turn driven, through a belt 29, from a sheave 30 fast on the usual main cam shaft 31 of the machine. Due to crossing of the belt 23, the sheave 21 of clutch 19 is constantly driven contrary to the direction of rotation of the pulley 20 of clutch 18 for a reason later on explained.

The clutch 18, see Fig. 4, comprises a core spool 35 which, in practice, is made of electrical steel and secured to the take-up roll shaft 15 by means of a key 36, and upon which a magnet coil 37 is wound. The coil 37 is enclosed within a shield 38 jointly formed by a cylindric mid section 39 preferably of non-magnetic material such as aluminum, two end ring sections 40 and 41, preferably of steel, which extend about the flanges of the spool 35, and a sealing disk 42 likewise of aluminum which is secured to the outer face of one of the flanges. The armature element of the electro-magnet is in the form of a cylindric housing 45 which surrounds the shielded coil element with intervention of a slight circumferential clearance 43. The end walls 46 and 47 of the

housing 45 have axial bosses 48 and 49 which surround the shaft 15 with interposition of ball bearings 50 and 51. The body of the housing 45 is constructed of electrical steel, and the end walls 46 and 47 of non-magnetic material which, like the parts 39 and 20 of the coil shield, may be of aluminum. The sheave 20, it will be noted, is secured to the boss 49 of the housing 45. As conventionally indicated, the housing 45 is filled with a suitable magnetic fluid medium which may consist of a mixture of light machine oil and carbonyl iron powder, leakage of the fluid past the bearings 50 and 51 being prevented by sealing disks 53 and 54. The slip clutch 19 is an exact duplicate of the clutch 18 and has not therefore been separately illustrated in detail, the magnet coil only of the former being shown in dotted lines at 55. The leads 56, 57 and 58, 59 from the magnet coils 37 and 55 are threaded through a longitudinal slot in shaft 15 whereto are secured beyond the clutch 19, three current collecting rings 60, 61 and 62. As shown, in Fig. 5, magnet coil leads 56 and 58 are connected to the center ring 61, and the leads 57 and 59 to the outer rings 60 and 62 respectively.

Direct current for energizing coils of the slip clutches 18 and 19 is obtained, through a rectifier 65 (Fig. 5), from the secondary winding of a transformer 66, the primary winding of said transformer being connected across an alternating current power line 67 in which a hand switch 68 is interposed. By means of a conductor 69, the brush 70 bearing on the central collector ring 61 is connected to the terminal 71 of the secondary of transformer 66. Extending from the other terminal 72 of the transformer secondary is another conductor 73 which extends to a circuit 75 whereof the return wire 76 is connected to the brush 77 of collector ring 60. Arranged in parallel across the wires 78 and 79 of the circuit 75 are branches 80, 81, 82, 83 and 84 containing individual switches 86, 87, 88, 89 and 90, individual separately-adjustable resistances 91, 92, 93, 94 and 95. For the actuation of the switches 86-90 we have provided rotary cams 96, 97, 98, 99 and 100 on an auxiliary cam shaft 101 which, see Figs. 1-3, is rotatively supported in a bearing bracket 102 on the bottom front rail 103 of the machine. The shaft 101 is adapted to be intermittently rotated through picking of a ratchet wheel 105 thereon, by a pawl 106 on the arm 107 which is oscillatable about said shaft. It is to be noted that the ratchet wheel 105 has one tooth in excess of the number of the cams 96-100, and that the rises of said cams are circumferentially spaced for actuation of the switches 86-90 in succession during each full rotation of said shaft which occurs once for each knitting cycle of the machine. As best shown in Fig. 1, the pawl arm 107 is operated, through a link rod 108, by a lever 109 having a cam finger 110 in the path of lugs or buttons, such as the one indicated at 111, on the timing chain 112 of the machine. As usual in knitting machines of the kind illustrated, the timing chain 112 is intermittently progressed by known mechanism which has not been illustrated. It is to be understood that lugs 111 corresponding in number to the teeth of ratchet wheel 105 are provided on the chain 112, these being suitably spaced to function at the proper times as hereinafter more particularly pointed out. Connected in parallel across leads 115 and 116 (Fig. 5) of a supplemental circuit 117 are branch conductors 118, 119 respectively containing individual switches 120, 121 and in-

dividual separately-adjustable resistances 122 and 123, one of said leads being tapped into the conductor 73 at 125, and the other connected to the brush 126 of collector ring 62. The brushes 10 and 77 and 126 are spring biased (see Figs. 1 and 4) and supported in a holder 127 which is carried by a bracket 128 on another transverse frame 129 of the knitting machine. Again referring to Fig. 5, the switches 120 and 121 are arranged to be actuated respectively by rotary cams 130 and 131 on the main cam shaft 31 of the machine when said shaft is axially shifted during the welt-turning and narrowing phases of each knitting cycle, the rises of these cams being circumferentially spaced as shown to close said switches at the proper times, also as presently explained in greater detail.

Operation

The armature elements of the clutches 18 and 19 are constantly driven in opposite directions as indicated by the arrows thereon in Fig. 1. At the beginning of a stocking knitting cycle, the chain 112 is actuated to bring the first lug 111 of the series thereon beneath the finger 110 of arm 109 as shown in Fig. 1. As a consequence, the ratchet wheel 105 is picked to the extent of one tooth by the pawl 106, and the shaft 101 correspondingly shifted rotatively for closure of the switch 86 by the cam 96 as shown in Fig. 5. Under these conditions, current flows from the terminal 72 of the secondary of transformer 66 by way of conductors 73, 78, 80, switch 86, resistance 91, conductor 76, collector ring 61 and conductor 69, to the terminal 71 of said transformer secondary to energize the magnet coil 37 of clutch 18. The resistance 91 is adjusted to set up in the coil 37 of clutch 18 a flux strength sufficient for the maintenance of a definite degree of torsion upon the roll 10 so that the fabric of the stocking blank is gradually taken up, while slippage takes place between the relatively movable parts of the clutch for maintenance of the desired tension without imposition of undue strain upon the fabric loops. When the main cam shaft 31 of the machine is shifted during the welt closing stage of the knitting cycle, the switch 120 is actuated by the cam 130, with resultant establishment of current flow from the secondary winding of the transformer 66 by way of conductors 115, 118, switch 129, resistance 122, conductor 116, collector ring 62, coil 55 of clutch 19, collector ring 61 and conductor 69, to the terminal 71 of said transformer. The resistance 122 is adjusted to set up in the clutch 19 a flux strength sufficient for creation of a reverse torsional influence upon the roll 10 to counteract, in part, that induced by the clutch 18, for temporary reduction to a corresponding degree, in the tension maintained on the fabric of the stocking blank while the welt is being closed. Soon after the welt is completed, the ratchet 105 is picked another tooth to turn the auxiliary cam shaft 101 through another increment by which the cam 96 is advanced to open switch 86, and the cam 97 to close switch 87. Under these circumstances, current will continue to flow in the coil 37 of the clutch 18 except for being modified now by the resistance 92 which is so adjusted that the torsional effect upon the roll 10 is somewhat reduced and the tension on the fabric correspondingly lessened. The decreased degree of tension is maintained throughout the knitting of the boot of the stocking blank except during the fashoring phases of this stage of the knitting

when the main shaft 31 of the machine is shifted occasionally. By these shiftings of the main shaft 31, the cam 131 momentarily closes the switch 119 for energization of the coil 55 of the clutch 19, the current strength being however then reduced by the resistance 123 which is adjusted to correspond substantially with the setting of the resistance 122 so that the counter-acting influence of the clutch 19 upon the clutch 18 will be about the same as during the welt closing stage previously described. Through successive rotary shifts of the shaft 101 determined by the disposal of the lugs 111 on the timing chain 112, the switches 88, 89 and 90 will be closed in sequence at the proper times and held closed respectively during the heel, foot and toe knitting phases of the machine with attendant modification of the current strength in the magnet coil of the clutch 18 in accordance with the adjustment of the respective resistances 93, 94 and 95 in the circuit 75. By the pick of the sixth or last tooth of the ratchet wheel 105, the shaft 101 will be placed in a neutral position with all of the switches 80—84 open and the circuit 75 dormant until a succeeding knitting cycle is initiated.

While, for the purpose of exemplification herein, we have shown and described our invention in connection with a straight stocking machine, it is not to be considered as limited to such use, since, by suitable modifications within the scope of the broader of the appended claims, it can be readily adapted to other types of knitting machines, as well as to textile machines generally where it is advantageous or necessary to vary the tension maintained upon the fabric as it is drawn away from the producing instrumentalities by take-up rolls.

Having thus described our invention, we claim:

1. In fabric draw-off mechanism for a straight flat fashioned stocking blank knitting machine having a fabric take-up roll, an electro-magnetic fluid slip clutch for driving the roll; and means automatically operative, during the knitting of different portions of a stocking blank to change the current flow through the magnetic clutch and thereby vary the torsional influence of the latter upon the roll, said means including a circuit in which a plurality of switches and individually-associated separately-adjustable resistances are connected in parallel with the coil of the magnetic clutch, a shaft with rotary cams thereon for actuating the respective switches, and provisions for imparting intermittent rotary shifts to the shaft for successive actuation of the several switches at the required times during each knitting cycle.

2. In fabric draw-off mechanism for a straight flat fashioned stocking blank knitting machine having a fabric take-up roll and a timing chain; an electro-magnetic fluid slip clutch for driving the roll; and means automatically operative, during the knitting of different portions of a stocking blank to change the current flow through the magnetic clutch and thereby vary the torsional influence of the latter upon the roll, said means including a circuit in which a plurality of switches and individually-associated separately-adjustable resistances are connected in parallel with the coil of the magnetic clutch, a shaft with a ratchet wheel thereon and with rotary cams for actuating the respective switches, and provisions controlled from the timing chain for intermittently picking the ratchet wheel and thereby causing the cams on the shaft to successively ac-

tuate the several switches at the required times during each knitting cycle.

3. In fabric draw-off mechanism for a straight flat fashioned stocking blank knitting machine having a fabric take-up roll, a timing chain and a main cam shaft which is axially shiftable for welt closing and fashioning purposes, an electro-magnetic fluid slip clutch for driving the roll; means automatically operative, during the knitting of different portions of a stocking blank to change the current flow in the coil of the magnetic clutch and thereby vary the torsional influence of the latter upon the roll, including a circuit in which a plurality of switches and individually-associated separately-adjustable resistances are connected in parallel with the coil of the magnetic clutch, an auxiliary cam shaft with rotary cams thereon for successively actuating the switches at the required times during each knitting cycle, and provisions controlled from the timing chain of the machine for intermittently rotating the shaft; a normally inactive second electromagnetic fluid clutch having a tendency to reversely rotate the roll; and rotary cams on the main cam shaft for actuating the last mentioned switches respectively when said shaft is shifted during the welt closing and fashioning phases of the knitting for energization of the coil of the second clutch, whereby the torsional effect of the first clutch upon the shaft is partially counteracted with consequent modification of the tension imposed upon the fabric.

4. In fabric draw-off mechanism for a textile machine, a fabric take-up roll, a driving slip clutch associated with the roll, means automatically operative to change the torsional influence of the clutch upon the roll and so vary the tension imposed upon the fabric at different predetermined stages in the knitting cycle of the machine, and supplemental means automatically operative at predetermined times to partially counteract the torsional effect of the slip clutch upon the roll and thereby modify the tension imposed upon the fabric during certain stages of the knitting cycle.

5. In fabric draw-off mechanism for a straight flat fashioned stocking blank knitting machine, a fabric take-up roll, a slip clutch for driving the roll, means automatically operative to vary the torsional influence of the clutch upon the roll and thereby modify the tension maintained on the fabric during predetermined stages of the knitting cycle of the machine, and supplemental means automatically operative to partially counteract the torsional effect of the clutch upon the roll and thereby modify the tension imposed during welt closing and during fashioning phases of the knitting.

6. In fabric draw-off mechanism for a textile machine having a fabric take-up roll, an electro-magnetic slip clutch for driving the roll, means automatically operative to vary current flow to the magnetic clutch and so change the torsion influence of the latter for variation in the tension imposed upon the fabric during different predetermined stages in the knitting cycle of the machine, and supplemental means operative at predetermined times during certain stages of the knitting cycle to partially counteract the torsional effect of the clutch and so modify the tension imposed upon the fabric.

7. In fabric draw-off mechanisms for a textile machine having a fabric take-up roll, an electro-magnetic slip clutch for driving the roll, means automatically operative to vary current flow to

the magnetic clutch and so change the torsion influence of the latter for variation in the tension imposed upon the fabric during different predetermined stages in the knitting cycle of the machine, a second normally-inactive fluid clutch 5 tending to reversely rotate the roll, and supplemental means automatically operative to energize the second clutch during certain stages of the knitting cycle and thereby partially counteract the torsional effect of the first mentioned clutch.

8. In fabric draw-off mechanisms for a straight flat-fashioned stocking blank knitting machine having a fabric take-up roll, an electro-magnetic slip clutch for driving the roll, means automatically operative during the knitting of different portions of a stocking blank to vary the current flow to the magnetic clutch and thereby modify the tension imposed upon the fabric, and supplemental means automatically operative 15 to partially counteract the torsional effect of the clutch upon the roll during welt closing and the fashioning phases of the knitting cycle.

9. In fabric draw-off mechanisms for a straight flat-fashioned stocking blank knitting machine 20 having a fabric take-up roll, an electro-magnetic slip clutch for driving the roll, means auto-

matically operative during the knitting of different portions of a stocking blank, to vary the current flow to the magnetic clutch and thereby modify the tension imposed upon the fabric, a second magnetic fluid clutch tending to reversely rotate the roll, and supplemental means automatically operative to energize the second clutch and thereby partially counteract the torsional effect of the first clutch so as to modify the tension imposed upon the fabric during the welt closing and the fashioning phases of the machine.
